UNITED STATES PATENT OFFICE.

GOTTLOB BINDER, OF ROCHESTER, NEW YORK, ASSIGNOR TO AMERICAN LAUNDRY MACHINERY CO., OF CINCINNATI, OHIO, A CORPORATION OF OHIO.

IRONING-MACHINE.

1,129,161.

Specification of Letters Patent. Patented Feb. 23, 1915.

Application filed December 4, 1913. Serial No. 804,666.

To all whom it may concern:

Be it known that I, GOTTLB BINDER, of Rochester, in the county of Monroe and State of New York, have invented certain new and useful Improvements in Ironing-Machines; and I do hereby declare the following to be a full, clear, and exact description of the same, reference being had to the accompanying drawings, forming a part of this specification, and to the reference-numerals marked thereon.

My invention has for its primary object to provide certain improvements in the class of ironing machinery more commonly known as bosom presses, which embody generally a garment or bosom support and a bed which are relatively movable to be brought into pressing relation with each other, the garment support being provided with neck-band engaging devices that are expandable so as to fit neck-bands of different sizes, and more particularly the invention contemplates a construction that will afford means for giving a smooth finish to the shirt bosom by stretching and straightening it properly on the bosom board and ironing close up to the neck-band.

My invention comprises in a more specific sense, a plate that is carried by the bed and is adapted to engage the bosom of the shirt as the garment support and bed come into pressing relation with each other, and means for so controlling the operation of the plate as to move it into intimate engagement with the neck-band holding devices, and thus enable the bosom of the shirt to be ironed completely, without slighting that portion which lies immediately adjacent to the neck-band and without producing any unevenness or wrinkled portions in the fabric.

A further object of my invention resides in providing the bed with a movable section which under normal conditions engages the neck-band engaging devices when in pressing relation, and may be thrown out of its operative position to afford an unobstructed recess when a collar-attached shirt is ironed.

To these and other ends the invention consists in certain improvements and combinations of parts all as will be hereinafter more fully described, the novel features being pointed out in the claims at the end of the specification.

In the drawings: Figure 1 is a view in side elevation, with parts in section, showing a

bosom press of a usual type, equipped with a preferred embodiment of the invention; Fig. 2 is a detail view of a portion of Fig. 1; Fig. 3 is an enlarged side elevation of the bed and garment support, before the latter is raised; Fig. 4 is a similar view, showing the garment support as it commences to move upwardly, the bosom plate being lowered; Fig. 5 is a plan view of a portion of the bosom board and the neck-band engaging devices, with the bosom plate overlying the board; Fig. 6 is a plan view, partially in section, showing a portion of the garment support and bed, the movable section of the bed being in its inoperative position; Fig. 7 is a plan view of the bed with the movable section appearing in full lines in operative position; Fig. 8 is a sectional view on the line 8^a—8^a of Fig. 7; Fig. 9 is an enlarged side elevation of the locking means, and 75 guide, which control the movements of the bosom plate, and Fig. 10 is a sectional view on the line 10^a—10^a of Fig. 7.

Similar reference numerals throughout the several figures indicate the same parts. 80

In pressing machines of this character, employed for ironing shirt bosoms, the chief difficulty heretofore experienced has been in obtaining a smooth, unwrinkled surface when the shirt is finished, and in ironing it as perfectly over the area extending immediately around the neck-band as the other parts of the bosom. The provision of a thin metal plate to overlie the bosom of the shirt between the garment support and the bed when the parts are in pressing relation, has been suggested and tried, but it has been difficult to support and control the plate in such a manner as to bring it into effective relation with the garment, or to insure a close engagement between the plate and the neck-band holding devices. If this close engagement is not brought about, there is a small space surrounding and immediately adjacent to the neck-band which is not pressed, thus detracting from the good results that may be secured on the other portions of the bosom, and I have therefore provided a bosom plate for this purpose which is so arranged that it will always move into close contact with the neck-band holding devices, and be retained there securely during the pressing operation. 105

To illustrate my improvement, I have shown a machine provided with a stationary

bed and a garment support provided with a bosom board and movable upwardly into engagement with the bed, although the invention is not limited in its broad aspect to this particular form of machine. In the present arrangement, 1 designates a vertically movable support, provided with a bosom board 2, neck-band engaging devices 3 and 4 and the neck-band clamp 5, all of which form no part of my present invention, and therefore do not require an extended description, the operation of certain parts in this type of machine being well understood by anyone versed in the art.

6 designates the stationary bed which is suitably secured to the head 7, the latter being mounted upon the standards 8 extending from the base 9, and mounted on the bed 6 is a flexible bosom plate 10, constructed of thin brass or other metal or suitable material. Arranged at one end of said plate are ears 11 in which are mounted rollers 12 for engagement with the flanges 13 on the bed as shown in Figs. 3 and 4. The bed is further provided with inclined guides 14 fixed thereon, and which coöperate with the plate when the latter moves downwardly, to cause it to come into close engagement with the neck-band clamp 5. To this end, the plate 10 is preferably provided with a pair of upstanding arms 15 which may be provided with anti-friction rollers 16 that engage the guides as shown.

17 designate locking abutments provided on the bed and arranged to receive the latches 18 which are pivoted upon the plate in advance of the arms 15 and include lugs 19 that project over the abutments 17 when the parts are in the position shown in Figs. 1 and 3, and thus hold the plate raised. The arms 15 are recessed to receive the springs 20 arranged about the posts 21, and adapted to be engaged by the latches 18 for a purpose that will presently appear.

45 It will be seen that the plate 10 is normally raised as shown in Fig. 3 being held in its upward position by the latches engaging the locking abutments 17, and it is desirable to provide means for automatically releasing the latches, to permit the plate to fall simultaneously with the initial upward movement of the garment support. To this end, I prefer to connect with the latches the main controlling device, or treadle, 50 which opens the valve to permit fluid pressure to operate the work support, and this is accomplished in the present embodiment by providing a pair of standards 22 upon the bed. Journalized in said standards is a 55 rock shaft 23 upon which are fixed levers 24, these being slotted at 25 and arranged to engage projections 26 upon the latches, as shown in Fig. 3. The rock shaft 23 carries at its outer end a lever 41 to which 60 is pivoted a connecting rod 42, the latter

being in turn connected to an arm 43 fixed upon the main operating shaft 27 which controls the fluid pressure valve.

28 is the usual starting treadle connected to the shaft 27, while 29 is the releasing treadle which is operated to release the garment support. By this construction, the parts being in the first instance in the position shown in Fig. 3, when the starting treadle is operated, the levers 24 are actuated toward the right of Fig. 3, moving the latches laterally to free them from the locking abutments. This permits the plate to drop as shown in Fig. 4, its movement being downwardly at an angle to the perpendicular due to the inclination of the guides 14, until it comes into contact with the neck-band clamp 5. This movement of the plate causes the bosom of the garment to be smoothed and straightened while the garment support is moving upwardly by reason of the squeezing action of the plate against the garment, starting at the neckband and proceeding toward the lower end of the garment, and at the limit of this upward movement, the parts are positioned as shown in Figs. 8 and 9, the plate being held in tight engagement with the neck-band clamp, and thus coöperating with every portion of the bosom up to and immediately surrounding the neck-band. It will be seen that during such upward movement of the plate, it travels in a vertical direction, moving independently of and free from the guides 14 until it assumes the position shown in Figs. 100 8 and 9. The parts remain in this position until the releasing treadle is operated which immediately causes a reverse movement of the levers 24, actuating them so as to move the latches to the position shown in dotted lines in Fig. 9. This compresses the springs 20, and as soon as the garment support moves downwardly far enough to release the bosom plate, the springs act at once to throw the arms 15 to the position shown in Fig. 3, where they engage the inclined guides, and the parts are ready for another operation.

In order to accommodate the neck-band clamp and neck-band engaging devices which project above the surface of the bosom board, the bed is recessed, the recess ordinarily being of such depth as will permit the portion of the bed at the top of the recess to contact with the neck-band engaging devices when the parts are in pressing relation, but this type of machine is not practicable for ironing shirts that have attached collars, as there is no space to receive the collar. In order to adapt the machine to this style of garment, I provide the stationary bed with a movable section which is normally disposed above the bottom of the recess just referred to and is adapted to contact with the neck-band en-

gaging devices when in such position. When ironing a collar-attached shirt, however, this movable section can be adjusted to an inoperative position leaving a free space that is unobstructed to receive the collar, while the bosom is ironed. The collar may subsequently be ironed by hand or in any other suitable manner. To this end, I prefer to arrange upon the bed a movable block or rigid plate 30 which is preferably pivoted at 31 and provided with a handle 32 by which it can be moved. The plate 30 embodies a body portion which is shaped to conform to the recess that receives the neck-band engaging devices, and is provided with a recess 33 to permit the escape of steam from the bosom board when the parts are in pressing relation. The bed is grooved as at 34; said groove surrounding the recess, and receiving the edge of the block 30 as shown in Fig. 8. When a collar-attached shirt is to be operated on, the block 30 is swung to the position shown in dotted lines in Fig. 7, and it may be held in its operative or inoperative position by means of spring actuated plungers 35 seated in recesses in the bed and arranged to engage depressions in the block, so as to hold the latter against accidental movement.

30 I claim as my invention:

1. In an ironing machine, the combination with a bed, of a garment support, one movable into pressing relation with the other, and neck-band engaging devices movable with the garment support, the bed including a movable section normally coöperating with the neck-band engaging devices and adapted to be moved to a position where it will not engage the neck-band engaging devices when the parts are operated.

2. In an ironing machine, the combination with a bed, of a garment support, one movable into pressing relation with the other, and neck-band engaging devices movable with the garment support, the bed including a recess to receive said neck-band engaging devices and a block movably arranged in said recess and coöperating with the neck-band engaging devices when in normal position.

3. In an ironing machine, the combination with a bed, of a garment support, one movable into pressing relation with the other, and neck-band engaging devices movable with the garment support, the bed being recessed to receive the neck-band engaging devices and including a pivotally mounted block normally disposed within the recess.

60 4. In an ironing machine, the combination with a bed and garment support, one movable into pressing relation with the other, of a bosom plate mounted on the bed and movable downwardly to engage a garment on the support, and inclined guides

coöperating with the plate to direct its downward movement, said plate being movable upwardly to its normal position independently of said guides.

5. In an ironing machine, the combination with a bed and garment support, one movable into pressing relation with the other, of a bosom plate mounted on the bed and movable downwardly to engage a garment on the support, and means for causing the plate to move downwardly at an angle to the perpendicular, the plate being movable upwardly in a vertical direction.

6. In an ironing machine, the combination with a bed and garment support, one movable into pressing relation with the other, of a bosom plate mounted on the bed and movable downwardly to engage a garment on the support, and guides coöperating with the plate during its downward movement, the plate being movable free of the guides during its return or upward movement.

7. In an ironing machine, the combination with a bed and garment support, one movable into pressing relation with the other, of a bosom plate mounted on the bed and movable downwardly to engage a garment on the support, guides coöperating with the plate during its downward movement, a locking abutment on the bed, a latch pivoted to the plate and normally engaging said abutment, and automatically controlled means acting to move the latch out of locking engagement with said abutment when the machine is operated.

8. In an ironing machine, the combination with a bed and garment support, one movable into pressing relation with the other, of a bosom plate mounted on the bed and movable downwardly to engage a garment on the support, inclined guides arranged on the bed, arms on the plate adapted to engage the guides during its downward movement, a latch pivotally mounted on the plate, a locking abutment on the bed with which said latch coöperates when in normal position, and automatically controlled means acting to disengage the latch from said abutment when the machine is operated to permit the plate to move downwardly into engagement with the garment.

9. In an ironing machine, the combination with a bed and garment support, one movable into pressing relation with the other, of a bosom plate mounted on the bed and movable downwardly to engage a garment on the support, inclined guides arranged on the bed, arms on the movable plate arranged to engage the guides during its downward movement, pivoted latches disposed on the plate in spaced relation to said arms, springs mounted on said arms and engaging the pivoted latches, locking abutments carried by the bed with which

said latches normally engage, and automatically controlled means acting to disengage the latches from said abutments when the machine is operated.

- 5 10. In an ironing machine, the combination with a bed and garment support, one movable into pressing relation with the other, of a bosom plate mounted on the bed and movable downwardly to engage a garment on the support, arms on the plate, guides arranged on the bed and co-operating with the arms on the plate when the latter moves downwardly, locking abutments mounted on the bed, pivoted latches carried by the plate and normally in engagement with said abutments, means for moving the plate laterally to bring the arms into engagement with said guides, the plate being movable upwardly independently of the guides, and automatically controlled means acting to release the latches from the abutments when the machine is operated.

tion with a bed and garment support, one movable into pressing relation with the other, of a bosom plate mounted on the bed and movable downwardly to engage a garment on the support, arms on the plate, guides arranged on the bed and co-operating with the arms on the plate when the latter moves downwardly, locking abutments mounted on the bed, pivoted latches carried by the plate and normally in engagement with said abutments, means for moving the plate laterally to bring the arms into engagement with said guides, the plate being movable upwardly independently of the guides, and automatically controlled means acting to release the latches from the abutments when the machine is operated.

11. In an ironing machine, the combination with a bed and garment support, one movable into pressing relation with the other, of a bosom plate mounted on the bed and movable downwardly to engage a garment on the support, arms on the plate, guides arranged on the bed and co-operating with the arms on the plate when the latter moves downwardly, locking abutments mounted on the bed, pivoted latches carried by the plate and normally in engagement with said abutments, means for moving the plate laterally to bring the arms into engagement with said guides, the plate being movable upwardly independently of the guides, and automatically controlled means acting to release the latches from the abutments when the machine is operated.

GOTTLOB BINDER.
